UNITED STATES PATENT OFFICE.

ALEXANDER CONSTANTINE IGNIDES, JR., OF LONDON, ENGLAND.

MEANS FOR CONTROLLING ELASTIC FLUIDS.

Application filed October 31, 1919. Serial No. 334,870.

To all whom it may concern:

Be it known that I, ALEXANDER CONSTANTINE IGNIDES, Junior, a subject of the King of Great Britain and Ireland, and residing at 34 Porchester Terrace, London, W. 2, England, have invented certain new and useful Improvements in Means for Controlling Elastic Fluids, of which the following is a specification.

- 10 This invention relates to means for maintaining a constant relationship between the pressures of two elastic fluids by the movement of a partition, floating bell, or the equivalent subjected upon opposite sides to 15 the pressures of the said fluids, and by its movement operating valves which control their passage.

In United States application, Serial No. 137,885 and the further application Serial No. 334,877 divided therefrom a pressure balancing device is described, in which a bell floating in a liquid seal forms a partition between two chambers, and is subjected to the pressure of air or the like in one 25 chamber and a combustible gas in the other, said air and gas entering said chambers each through a double beat or balanced valve, actuated by the movements of said bell to maintain a constant determined relationship 30 between the pressures of the two elastic fluids which pass at the controlled pressures from said device to gaseous fuel combustion appliances.

During operation, a drop in the pressure 35 of one of the fluids supplied to the device results in the valve controlling that fluid being opened to a greater extent, while the valve controlling the other fluid which retains its pressure is correspondingly closed. 40 Under these conditions, the immediate result of the complete failure of one supply, say for example, the air, is that the gas is promptly shut off, and would remain so, provided the necessary pressure was maintained upon the surface of the bell, that is, in the space beyond the regulating valve communicating with the main leading to the combustion appliances. Maintenance of pressure in the main is however unlikely unless 45 the failure were noticed, and immediate steps taken to prevent the further escape of fluid therefrom. Thus, in the event of the air supply failing as indicated, re-opening of the gas regulating valve and consequent 50 leakage of gas is likely to result.

The foregoing constitutes a danger which

it is the object of the present invention to overcome.

The invention consists in a fluid pressure balancing device having a movable partition subjected upon opposite sides to the pressures of two elastic fluids after their passage through valve means actuated by the movement of said partition, whereby their pressures are controlled so that they 60 assume a constant relationship at the outlets of said device, in which upon failure of the supply of one fluid a communication is opened to allow the uncontrolled supply pressure of the other fluid to act upon the 65 partition and completely stop the passage of said other fluid through the device until a supply of the first fluid is restored.

The invention further consists in an elastic fluid pressure balancing device according 75 to the preceding paragraph in which upon failure of one fluid the movement of the partition, due to the pressure of the other fluid in addition to completely closing the regulating valve for the latter, also closes 80 communication between the bell and the outlet for said fluid, and opens communication to said bell from the inlet passage in front of the regulating valve, thus holding said regulating valve tightly closed until the 85 pressure of the first fluid is restored.

The invention further consists in a pressure balancing device according to the preceding paragraph in which an aperture admitting gas from the outlet of the regulating 90 valve to the surface of the bell is adapted to be closed by a valve which is seated at or about the time that the gas regulating valve is seated; while the additional unbalanced force exerted upon the bell due to failure of 95 the air pressure opens a valve leading from the gas inlet passage to the surface of the bell.

The invention further consists in a device as indicated having a conduit leading from 100 the space adjoining the underside of the bell to a chamber the entry to which is controlled by the gas regulating valve, and from which the outlet passage opens, said conduit being provided with a shut-off valve which is seated 105 contemporaneously with the gas regulating valve, while a hollow spindle connecting said shut-off and regulating valve is provided with a spring-loaded valve which opening under the additional force admits the gas at 110 full supply pressure from the inlet passage to the under surface of the bell.

The invention also consists in the improvements in or relating to means for controlling gaseous fluids as hereinafter described.

5 Referring now to the accompanying drawings:

Figure 1 is a sectional elevation of an improved fluid pressure balancing device in accordance with this invention, and

10 Figure 2 is an enlarged detail of the gas and communication valves.

Figure 3 is a diagram of the levers and connections.

In carrying the invention into effect in one 15 convenient form, as shown by way of example in the drawings, two double beat valves *a* and *b* having between them a pressure bell *c* floating in a liquid seal *d* are positioned within an upright casing formed of 20 the various members *e*—*e*⁸.

The double beat valve *b*, which in the embodiment illustrated is intended for regulating the air, is of considerably larger dimensions than the gas valve *a*, which is suitable 25 for comparatively rich gas. The valve *b* is positioned in a cylindrical casing *e'* formed as a casting, and control apertures *f*¹ *f*², in the air inlet passage *f*.

Upon the side of the casing *e'* opposite to 30 the inlet *f* is an outlet branch *g* leading from the surrounding space to the main feeding the combustion appliances. The casing *e'* is provided at the upper end with a removable cover *e* for giving access to the valve *b*, 35 and at its lower end is jointed by means of the section *e*² to the tank *e*³ containing the floating bell hereinafter described.

The bell *c* forming a moving partition between the air and gas and actuating the 40 valves by tension members and delicately balanced levers as shown diagrammatically in Figure 3 and more fully described in the above mentioned applications, operates in an annular tank *e*³ preferably formed of stamped 45 material and having an out-turned flange round the upper edge of the outer shell by means of which the section *e*² is attached thereto. A domed top *h* corresponding in shape with the top of the floating bell *c* extends 50 from the inner shell of the annular tank *e*³, said domed top forming a support for the top of the bell when the latter is in its lowest position. The annular tank contains the liquid seal *d* and is seated within 55 a channel-shaped ring *e*⁴ supported upon a series of legs *e*⁵ preferably provided with height adjusting screws *i* at their lower ends for setting the structure truly upright.

A tube *j* depends from the centre of the 60 dome *h* to about the level of the bottom of the tank *e*³, said tube being connected to the top cover *e*⁷ of a cylindrical casing *e*⁶ containing the double beat gas regulating valve *a*. The casing *e*⁶ has a gas inlet passage *k* 65 with apertures *k*¹, *k*², controlled by the valve

a and a gas outlet branch *l*; being generally of a construction similar to that of the air valve casing. It is connected by suitable bracing members *e*⁹ with the legs *e*⁵ upon which the tank rests. The tube *j* which 70 forms a communicating passage leading from the underside of the bell *c* to the gas regulating valve casing *e*⁶ is fitted at the lower end with a shut-off valve *m* adapted to close the end of the tube, and thus prevent 75 communication between the under surface of the bell and the gas main leading from the outlet branch *l* to the combustion appliances. The valve *m* is connected to the upper member *a*¹ of the double beat gas regulating 80 valve *a* by a hollow spindle *n* opening to the gas inlet passage *k* by apertures *a*² in the underside of the hollow upper valve member *a*¹ so that a communication is formed between the ungoverned gas supply in the inlet 85 passage *k* and the underside of the bell *c*.

The hollow spindle *n* communicates through the chamber *m*¹ and ports *m*² in the screw plug *m*³ with the interior of the tube *j* and it is provided with a spring loaded 90 valve *o* held to its seat by a coiled spring *p* positioned within the chamber *m*¹.

The valve *o* is attached to the bottom of the tension member *q* forming the operating connection between the bell and the gas regulating valve *a*. Under all normal conditions of working the load exerted upon the valve *o* by the spiral spring *p* is sufficient to hold the valve tightly upon its seat so that the passage through the hollow spindle *n* into 100 the tube *j* remains closed, but under exceptional circumstances as hereinafter described the spring *p* is compressed and the valve is opened and admits the full uncontrolled supply pressure of the gas to the underside of 105 the bell *c*.

In the event of the air supply failing from any cause say for example due to slipping off or breaking of a driving belt or any other accident of a like nature, the unbalanced pressure of the gas acting upon the underside of the bell will operate to completely close the gas regulating valve *a*, and at the same time the shut-off valve *m*, which controls the open bottom of the tube *j* will be closed. The additional force due to the gas pressure being entirely unbalanced by any air will cause the spring *p* loading the valve *o* to be compressed so that the controlled pressure of the gas already below the 110 bell will then be reinforced by the full pressure of the gas supply passing through the hollow spindle *n*. The bell will therefore hold the double beat valve *a* and the shut-off valve *m* tightly upon their seats, and although the pressure in the gas valve casing *e*⁶ and in the main leading therefrom may gradually fall, due to leakage through any apparatus which it supplies, these valves 115 cannot possibly open and allow a further 120

125 130 135

supply of gas to pass through until the failure of the air supply has been discovered, and the pressure of the air restored to again press down the bell.

5 In a slightly modified form of the apparatus the gas valves *a* may close and the communication valve *o* be opened prior to the closing of the shut-off valve *m*. Under these conditions the member *n* will be extended above the communication valve *o* in hollow form, so as to form an abutment for the upper end of the spring *p*, or in other words, perform the function of the plug *m*². The shut-off valve *m* will be made a sliding fit upon the outside of the member *n*, and supported so that it is clear of its seat when the valve *a* is closed. The communication valve *o* or its spindle *q* will be adapted to engage the shut-off valve *m* after the communication valve *o* has opened, and as the communication valve *o* is lifted a further distance, the shut-off valve *m* will be moved upon the member *n* until it engages its seat and closes the passage *j*.

10 By the provision of the shut-off valve and by-pass provided by the hollow spindle the safety of a gaseous fuel supply system is greatly increased as it is practically impossible for an unnoticed leakage of gas to occur to any extent which can lead to a dangerous explosion.

Modifications in the pressure balance and the manner of applying a safety-shut-off may be made without in any way departing 35 from the spirit of this invention.

Having now described my invention, what I claim as new and desire to secure by Letters Patent is:—

1. In combination in a fluid pressure balancing device, a movable partition separating two fluids, two pressure balanced valves operated by said partition and adapted each to regulate one fluid, separate means whereby each of the said fluids after regulation 45 gains access to said partition, and valve means controlling the access means for one fluid which operate in the event of the supply of the other fluid failing to prevent the regulated pressure of the one fluid from acting upon the partition and permit the unregulated pressure of the said fluid to do so.

2. In combination in a fluid pressure balancing device adapted to maintain a constant relationship between the pressures of 55 two gaseous fluids, a movable partition separating said fluids, a pressure balanced valve operated by said partition and adapted to regulate one fluid, a pressure balanced valve connected to said partition and adapted to regulate the second fluid, a conduit whereby the second fluid after regulation gains access to said partition, a shut-off valve whereby said conduit is closed in the event of the supply of the first mentioned fluid failing 60 and a further valve which under such conditions

ditions permits the unregulated pressure of the second fluid to act upon the partition.

3. In combination in a fluid pressure balancing device adapted to maintain a constant relationship between the pressures of 70 two gaseous fluids, a movable partition separating said fluids, two double disc pressure balanced valves operated by said partition and adapted each to regulate one fluid, a conduit whereby a fluid after regulation 75 gains access to said partition, a shut-off valve whereby said conduit is closed, when the regulated pressure acting upon the partition undesirably exceeds the pressure upon the other side thereof, a passage from between the two discs of a regulating valve through said shut-off valve, a valve closing said passage and means whereby said last mentioned valve is opened upon the shut-off valve being closed.

4. In combination in a fluid pressure balancing device adapted to maintain a constant relationship between the pressures of two gaseous fluids, a movable partition separating said fluids, a double disc pressure balanced valve operated by said partition and adapted to regulate one fluid, a double disc pressure balanced valve operated by said partition and adapted to regulate the second fluid, a conduit whereby the second fluid 90 after regulation gains access to said partition, a shut-off valve whereby said conduit is closed in the event of the supply of the first mentioned fluid failing, a passage from between the two discs of the valve regulating 95 the second fluid leading through said shut-off valve, a resiliently pressed valve closing said passage and means for opening said valve to permit the unregulated pressure of the second fluid to act upon the partition 100 upon such a failure of the supply.

5. In combination in a gaseous fluid pressure controlling device, an upright casing, a movable partition dividing said casing into an upper and a lower compartment, valves 110 balanced in relation to the fluid pressures controlling the admission of fluids to said compartments, means connecting the lower valve to said partition, a conduit whereby the fluid after regulation by said valve gains 115 access to said partition, a shut-off valve whereby said conduit is closed in the event of the supply of the other fluid failing and a further valve which under such conditions permits the unregulated pressure of the fluid supply to the lower compartment to act upon the partition.

6. In combination in a gaseous fluid pressure controlling device, an upright casing, a movable partition dividing said casing into 125 an upper and a lower compartment, valves balanced in relation to the fluid pressures controlling the admission of fluids to said compartments, means connecting the lower valve to said partition, a conduit whereby 130

- the fluid after regulation by said valve gains access to said partition, a shut-off valve whereby said conduit is closed in the event of the supply of the other fluid failing, a further valve which under such conditions permits the unregulated pressure of the fluid supply to the lower compartment to act upon the partition, a lever fulcrumed in said casting, means connecting the diaphragm to said lever, a second lever fulcrumed in said casting, means connecting the valve in the upper compartment to said second lever, and means connecting said second lever with the first mentioned lever.
- 15 7. In combination in a fluid pressure balancing device, a movable partition separating two fluids, two pressure balanced valves operated by said partition and adapted each to regulate one fluid and means affecting one only of said fluids whereby upon failure of the supply of the other fluid a communication is opened to allow the uncontrolled pressure of the one fluid to act upon the partition and completely stop the passage until 20 a supply of the other fluid is restored.
8. In combination in a fluid pressure balancing device, a movable partition separating two fluids, two pressure balanced valves operated by said partition and adapted each to regulate one fluid, means whereby upon 25 failure of one fluid the movement of the partition completely closes the regulating valve for the other fluid, means controlling one only of said fluids whereby communication between the partition and the outlet for the 30 said other fluid is closed and means whereby communication between said partition and the inlet passage in front of the said closed regulating valve is opened, so that said regulating valve is held tightly closed until the 35 pressure of the first fluid is restored.
9. In combination in a fluid pressure balancing device adapted to maintain a constant relationship between the pressures of two gaseous fluids, such as gas and air, a movable partition separating said fluids, a pressure balanced valve operated by said partition and adapted to regulate the air, a pressure balanced valve operated by said partition and adapted to regulate the gas, a conduit whereby the gas after regulation gains access to said partition, a shut-off valve whereby said conduit is closed in the event of the supply of air failing and a further valve which under such conditions permits the unregulated pressure of the gas to act upon the partition and hold the gas regulating valve tightly shut until the air pressure is restored.
- 10 15 20 25 30 35 40 45 50 55 60

In testimony whereof I have signed my name to this specification.

ALEXANDER CONSTANTINE IONIDES, Jr.
